UNITED STATES PATENT OFFICE.

CLARENCE A. GODSHALK, OF PHILADELPHIA, PENNSYLVANIA.

LOCKED-NUT APPARATUS.

Application filed June 28, 1924. Serial No. 723,012.

To all whom it may concern:

Be it known that I, CLARENCE A. GODSHALK, a citizen of the United States, residing at Philadelphia, in the county of Philadelphia and State of Pennsylvania, have invented certain new and useful Improvements in Locked-Nut Apparatus, of which the following is a specification.

This invention relates to locked nuts, that is to say, nuts adapted to be applied to bolts from which they are removed from time to time as occasion may require, but which until the time of removal, it is desirable should be locked and held against any unauthorized manipulation, either by a meddler or a person maliciously inclined. It has for its object to improve means or apparatus for locking such a nut, including key-operated lock mechanism. While the invention may be put to a wide variety of uses it is especially adapted as a spare tire lock for automobiles, and in the accompanying drawings I have illustrated it as used in such connection.

25 Referring to the drawings—

Figure 1 is a sectional view of a spare tire carrier and lock embodying one form of my invention, the locking parts being shown in elevation.

30 Fig. 2 is a front view of the parts shown in Fig. 1.

Fig. 3 is a view similar to Fig. 1 illustrating another form of my invention; and

35 Fig. 4 is a front view of parts shown in Fig. 3.

Fig. 5 is a sectional view taken on the line VV of Fig. 1.

In the drawings 2 designates the ring or holder upon which is supported the rim of a spare tire. To this is riveted or otherwise secured a bracket 3 from which extends outwardly a screw-threaded bolt or pin 5 that passes freely through an opening in a clamp piece 4 that is adapted to engage with the tire rim and hold it upon the support 2. The parts thus far described are well known in the art and are standard equipment upon many automobiles. They may be varied in details of construction so far as my present invention is concerned.

50 A nut 6 engages with the bolt 5 and is employed to bear against the clamp piece 4 and hold it in place against the rim of the tire that may be mounted upon the support 2. A casing 7 is connected with or carried

by the nut, being either integral therewith or a separate piece and secured thereto as may be preferred, in the forms of invention herein illustrated the casing being an extension beyond the nut 6, preferably angular in cross section and larger than the nut.

8 designates a locking post located alongside the bolt 5, and the nut and casing 7 when applied to the bolt. This post is preferably a separable element, being provided at one end with a reduced portion or pin 9 that is adapted to pass through aligning openings 10, 10' formed respectively in the bracket 3 and clamp piece 4. In the form of my invention illustrated in Figs. 1 and 2 the post 8 has formed in its outer portion a perforation or opening 11, in which is mounted the body 12 of a lock, which may be of any suitable character, that represented being a pin tumbler lock operated by a key 21. In the face of the lock body there is formed a longitudinal groove or slot 14 into which projects the end of a screw or pin 13 seated in the post 8. This arrangement permits the casing to slide longitudinally in the opening 11.

The casing 7 carried by the nut is located opposite to the portion of the post 8 in which is mounted the lock body 12, and in such casing is formed a socket or recess 15 into which extends the inner end of the lock body when the parts are assembled as represented in Fig. 1. The lock represented is constructed with a rotatable barrel or cylindrical portion 23 eccentrically mounted in the body 12 and adapted to be turned by the key 21. To the inner end of the rotatable barrel 23 is secured a locking plate 16 which is eccentric to the body 12 and is adapted to have its outer end 24 enter a recess 17 provided therefor in the body of the casing 7 when the parts are moved by the key into locking position.

The parts thus far described will be used as follows: After a spare tire has been placed upon the holder the clamp piece 4 is slipped over the bolt 5 and forced into place to hold the tire rim by screwing the nut 6 upon the bolt.

When the nut has been properly tightened it is adjusted so as to bring the casing 7 to the position indicated in Fig. 1, which is made possible by employing a split elastic washer 22 between the inner face of the nut and the clamp piece 4. The post 8 carrying

the lock, the body 12 of which is now withdrawn as far as the pin 13 and slot 14 will permit, as indicated by dotted lines in Fig. 1, and with the locking plate 16 moved so that its end 24 is within the circle of the body 12, is now set, by inserting its reduced end 9 through the aligning openings 10, 10'. The lock body is then moved longitudinally so that its inner end enters the recess 15 in the casing 7 carried by the nut, and when it reaches the position indicated in full lines in Fig. 1 the key is turned and the plate 16 moved into the recess 17, after which the key may be removed. The parts are thus locked together, the nut 6 being held against rotation and the post 8 against removal. The several parts of the apparatus described are caused to fit each other with such accuracy that when united as described there is practically no looseness and play of parts, making the apparatus noiseless when subjected to vibration and leaving no undesirable open spaces between parts into which a tool might be inserted by one seeking to destroy the lock.

The opposing faces of the casing 7 and post 8, designated respectively 18 and 18', are preferably flat and parallel with each other when the parts are properly assembled, and are in contact or but a short distance apart. One of the parts, in the instance illustrated the post 8, is provided at its outer end with a flange 19 adapted to extend over the space between the faces 18 and 18' of the parts 7 and 8 and to occupy a recess or rabbet 20 formed in the body of the casing 7 to receive such flange. This arrangement prevents access to the lock body 12 through the space between the casing 7 and post 8 from the outside or ends of the latter. The parts 7 and 8 will ordinarily be formed of harder metal than that from which is constructed the lock body, and one seeking to remove the nut 6 might attempt to cut the lock body with a hack saw. The arrangement last described serves to prevent this.

In the form of my invention illustrated in Figs. 3 and 4, the lock body 12 is represented as being supported in the casing 7 carried by the nut, its free end being adapted to occupy an opening or socket 11' formed in the post 8'. Corresponding parts in the two sets of views are designated by the same reference characters, those employed in Figs. 3 and 4 having applied to them the exponent prime where the parts there designated are in any way different from those shown in the other views.

I prefer the arrangement shown in Figs. 1 and 2 because the lock and post 8 may be entirely removed when they are not in use. It frequently happens that the nut 6 is employed without its being desirable to have

it locked, and under such circumstances the post and lock may be entirely removed.

What I claim is:

1. The combination with a screw-threaded pin and a nut adapted to engage therewith, of a casing united to the nut so as to turn therewith, a removable post adapted to be set in position close to said casing, the post and casing having openings adapted to align one with the other, and a lock the body of which is adapted to fit and to be movable longitudinally in the opening in one of the said parts and to be moved so as to enter the opening in the other part and to be locked thereto.

2. The combination with a screw-threaded pin and a nut adapted to engage therewith, of a casing united to the nut so as to turn therewith, in which casing is formed a socket, a removable post adapted to be set and occupy a position close to the said casing, and a lock mechanism the body of which is supported in the post and is movable longitudinally relative thereto so its inner end may be caused to enter the socket in the casing connected with the nut, the lock being constructed to have locking engagement with the said casing.

3. The combination with a screw-threaded pin and a nut adapted to engage therewith, of a casing united to the nut so as to turn therewith, a post located close to the casing, the post and casing having openings adapted to align with each other, and a lock mechanism adapted to unite the post and casing and thus prevent the rotation of the nut, the lock bridging the space between the post and casing and one of the parts united by the lock having a flange that overlies the space between them.

4. Lock mechanism, comprising a screw-threaded nut carrying a casing, a separable post and a lock mechanism supported in one of these parts and movable longitudinally in its support, the other part being formed with an opening into which the lock enters, the lock being constructed to engage with the part into which it has entered, thereby locking together the post and casing carried by the nut.

5. Lock mechanism, comprising a screw-threaded nut carrying a casing, in which is formed a socket, a separable post and a lock mechanism mounted in the post and movable longitudinally in its mounting so that its end may be projected into the opening in the nut, the lock being constructed to engage with the casing carried by the nut when properly manipulated for the purpose of uniting the post and casing carried by the nut, and thus preventing the unauthorized movement of the latter.

CLARENCE A. GODSHALK.
